UNITED STATES PATENT OFFICE.

CHARLES J. HENSCHEL, OF BROOKLYN, NEW YORK.

ANNUNCIATOR-DROP.

1,393,685.

Specification of Letters Patent.

Patented Oct. 11, 1921.

Application filed April 25, 1919. Serial No. 292,759.

To all whom it may concern:

Be it known that I, CHARLES J. HENSCHEL, a citizen of the United States, residing at Brooklyn, county of Kings, and State of New York, have invented certain new and useful Improvements in Annunciator-Drops, of which the following is a full, clear, and concise description.

My invention relates to annunciator drops and admits of general use, but is of peculiar value in connection with annunciator drops of a type suitable for use on shipboard.

My invention contemplates a number of distinct objects among which are the following.

1. To provide mechanism, connected with the drop and controllable thereby, for locking the drop shutter positively after each movement thereof in either direction, and for positively releasing the shutter before each of its movements.

2. To so construct and arrange the drop shutter and various working parts that while the working parts are at all times readily accessible for inspection and repair, the shutter normally conceals the working parts from the view of persons casually glancing at the drop incidental to the normal use thereof.

3. To so construct and arrange the shutter and the rocking armature used for actuating the same that while the shutter is stopped in certain exact positions at the limits of its travel, the armature is allowed more or less freedom of position in starting and stopping, in order to avoid excessive shocks and mechanical strains upon the shutter and its connections; due to the inertia and momentum of the armature.

4. To give the various parts such form and arrangement as to increase the reliability and efficiency of the drop, and to enable it to be built up largely of sheet metal.

5. To mount the shutter to swing horizontally, thus avoiding the necessity to expend power to lift it in order to restore it to its normal position.

6. To discard the use of springs and to render the control of the shutter independent of the force of gravity.

7. To prevent the shutter from being shifted in position by shocks, jars or various accidental causes, and to render the control of the drop strictly electrical.

Reference is made to the accompanying drawing forming a part of this specification,

and in which like letters indicate like parts throughout the several figures.

Figure 1 is a plan view of the drop, the shutter appearing in its usual or normal position.

Fig. 2 is a side elevation of the same.

Fig. 3 is a section on the line 3—3 of Fig. 2, looking in the direction indicated by the arrows.

Fig. 4 is a fragmentary side elevation of the drop, the shutter being shown in its abnormal position, as registering a signal.

Fig. 5 is a perspective of the armature shaft, used for actuating the shutter.

Fig. 6 is a side elevation of another form of the drop, in which the shutter is mounted to swing horizontally.

Fig. 7 is an inverted plan or bottom view of the mechanism shown in Fig. 6, and in which I use a form of Geneva stop differing slightly from the one appearing in Figs. 2 and 4.

A pair of side plates 6, 7, are made of sheet metal, cut out or stamped out, and serve as a supporting framework for the parts. These side plates are provided with lugs 8, integral therewith. These lugs are by screws 9 held against a wall 10.

Two magnets are shown at 11, 12, and between these magnets are a number of cylindrical spacing blocks 13. Bolts 14 extend through the magnets and spacing blocks. These bolts also extend through washers 15 and through the side plates 6, 7, and serve to hold a number of the parts together.

There are two cores 16, one for each magnet, and each core carries a winding 17.

The magnet 11 is provided with a pair of poles 18, 19, and similarly the magnet 12 has two poles 20, 21.

A revoluble shaft 22 extends through holes in the side plates 6, 7, and is thus journaled upon and supported by these plates. Mounted rigidly upon the shaft 22 are two armatures 23, 24 each extending crosswise of the shaft and having enlarged ends. These two armatures are displaced relatively to each other by the angular distance of thirty degrees.

The armature 23 is associated with the magnet 21 and is located between the poles thereof, the armature 24 being similarly associated with the magnet 12 and disposed between its two poles.

When either magnet is energized the armature associated with it is energized by

magnetic induction from the poles of the magnet, and takes up such position as to extend squarely across the magnet, from pole to pole thereof.

5 When one armature is thus turned into the position just stated, the other armature is turned to an angular distance of thirty degrees away from its corresponding position. Thus one armature rocks the shaft 10 in one direction of rotation and the other armature rocks the shaft in the opposite direction; the extent of the movement being approximately thirty degrees or one twelfth of a complete revolution.

15 The armature shaft 22 carries a sector 25, secured rigidly upon it and used as a gear member for actuating the shutter, as hereinafter described. The sector 25 is provided with two arcuate edge portions 26, 27 and with a number of gear teeth 28 located 20 between these two arcuate sections.

The side plates 6, 7, are provided with extending portions 29, integral with them. A shaft 30 is supported by these extending 25 portions. The shaft supports a shutter 31, upon which is shown a graphic legend, for instance Chart room. The shutter 31 has generally the form of a flat panel, and is provided with a portion 32 serving as a 30 blind for concealing the magnets and other internal mechanism of the drop, while the shutter occupies its normal position as indicated in Fig. 2. That is to say, the portion 32 of the shutter prevents the casual observer from seeing the various working parts 35 of the drop, yet for the purposes of inspection and repair the working parts may be seen without difficulty.

The shutter is provided with a pair of 40 sloping portions 33 and with a pair of edge portions 34, 34^a the latter being bent parallel to each other and having feet 35 which are secured to the blind 32. The parts 31, 32, 33, 34 and 35 are made of a single integral 45 piece of sheet metal, cut or stamped out as desired. The sheet metal may be thin, say of thirty gage.

The edge portion 34 is so fashioned as to 50 present a pair of bearing surfaces 36, 37, and a number of gear teeth 38 interposed therebetween. The bearing surfaces 36, 37 are adapted to fit neatly against the respective surfaces 27, 26 of the sector 25, but are concave while the surfaces 27, 26 are convex. 55 The teeth 38 are shaped to mesh with the teeth 28 of the sector. The material of the sector is comparatively thick.

The rocking movements of the sector 25 cause rocking movements of the shutter 31, 60 the motion being transmitted through the teeth 28 and 38.

The sector 25 as a whole coacts with the adjacent parts 36, 37, 38 in such manner as to act as a Geneva stop. Thus while the 65 shaft 22 rocks back and forth and can stop

in positions more or less intermediate, the movements of the shaft 30 are limited with exactness. The result is that the shutter is always brought to the same position at the end of its travel in either direction and independently of the precise position in which the shaft is brought to a stop.

70 The sector 25 and the gear members driven by it are so proportioned that the ratio of the gearing is three to one.

75 When the magnet 11 is energized, the armature 24 assumes a strictly vertical position and the various movable parts take up their respective positions as indicated in Figs. 1, 2, and 3.

80 When, however, the magnet 12 is energized the armature 23 becomes strictly vertical and the various movable parts assume the positions indicated for them in Figs. 4 and 5.

85 The magnets 11, 12 are energized at different moments, each remaining energized for a moment only. For this purpose the circuits used for energizing the two magnets are independent of each other.

90 Thus generally speaking the magnet 12 is used to set the drop, or in other words to actively display a signal, and the magnet 11 is to restore the drop to its normal condition, so as to make merely a continuous passive 95 indication.

99 In the form of my device appearing in Figs. 6, and 7, the Geneva stop is of a type differing slightly from that shown in Figs. 2 and 4, and the shutter is mounted to swing horizontally so as to avoid the necessity of lifting it in order to restore it to its normal position.

105 The shutter appears at 35, and bears an appropriate legend, in this instance Chart room. The shutter is provided with a portion 32 serving as a blind, and with sloping portions 37. A part of the shutter 37^a is provided with a slot 38 and with a pair of arcuate edges 39, 40, extending from this slot. 110 A sector 41 carries a pin 42, which enters the slot 38 and causes the shutter to rock.

115 If the shutter is to swing horizontally, however, the position of the legend Chart room upon the shutter is changed accordingly, as will be noted from Fig. 6. In this instance the armatures 23, 24, are displaced relatively to each other by sixty degrees instead of by thirty degrees as in the other form of Geneva stop.

120 With the exceptions noted the structure and action by the device shown in Figs. 6 and 7 is the same as that already described.

125 The operation of my device is as follows:

130 The parts being assembled and arranged as shown and as above described, the magnet 11 is connected in a circuit under the direct and immediate control of the operator, the magnet 12 being connected in a circuit 135

controllable from some other part of the ship.

Assuming the shutter to be in its normal position as indicated in Figs. 1, 2 and 3 if the distant operator closes the circuit through the magnet 12 the shutter is immediately shifted to such position as to display, to the operator in charge of the annunciator, the graphic legend carried by the shutter. 10 That is, the drop assumes the condition indicated by Fig. 4.

The signal being noted, the operator in charge of the annunciator now closes the circuit through the magnet 11. Thereupon 15 the shutter is restored to its normal position as indicated in Figs. 1, 2 and 3.

The action of the Geneva stop is quite important. Its tendency is to prevent undue shocks to certain parts of the mechanism. 20 That is to say, by aid of the Geneva stop the shutter is rapidly shifted from one of its extreme positions to the other, and at the limit of its movement in either direction is brought into an exact and certain position. The 25 armatures, however, are not stopped quite so abruptly or in such exact positions. Thus the armatures have more or less freedom of positions. This means that while the armature shaft always stops in certain proximate 30 positions, its stoppage is not extremely abrupt, and the position in which it stops at one time is not necessarily the same position in which it stops upon a different occasion. Thus while the shutter is actuated 35 by gearing driven by the armature shaft, the movement of the shutter shaft is positive while that of the armature is impositive.

The armatures, because of their weight, 40 have considerable inertia and momentum while in action. If, therefore, the armature shaft was brought to an exact position and there stopped abruptly, the resulting lost motion would subject the framework and 45 some of the movable parts to severe shock. The shutter, because of its lightness, can be stopped and started abruptly when brought into exact positions, without such shock. Hence I use the Geneva stop as a convenient 50 means for communicating motion from the armature shaft to the shutter shaft. By aid of the Geneva stop, the shutter is given the exact movements described, while the armatures and other movable parts are so 55 stopped and started as to avoid undue shock to them or other parts affected by them.

I do not limit myself to the precise mech-

anism shown, as variations may be made therefrom without departing from the spirit of my invention.

I claim:

1. The combination of a movable shutter, a rocking shaft connected with said shutter for actuating the same, an armature shaft, means for rocking the same into predetermined 60 positions, and gearing connected with said rocking shaft and driven by said armature shaft in order to actuate said rocking shaft, said gearing including means for stopping said rocking shaft positively in exact predetermined positions independently of the precise positions in which said armature shaft is stopped.

2. The combination of a movable shutter, a rocking shaft for supporting and actuating said shutter, an actuating shaft, means for turning the same into predetermined positions, and mechanism connected with both of said shafts for the double purpose of enabling said rocking shaft to be driven by said 75 actuating shaft and of locking said rocking shaft in exact predetermined positions independently of the precise positions in which said actuating shaft is stopped.

3. In an annunciator device the combination of an actuating shaft, electrically operated mechanism for rocking said shaft and stopping the same impositively and in positions determined approximately but not exactly, a display shutter, and mechanism 80 connected with said actuating shaft and controllable by movements thereof, said mechanism being also connected with said display 85 shutter for the double purpose of actuating said display shutter and of positively locking said display shutter in predetermined 90 positions when said positions are reached by said shutter.

4. In a device of the character described the combination of a shutter made of sheet 100 metal and having a display panel and a pair of supporting walls integral with said display panel, a rocking shaft secured to said supporting walls in order to support said shutter and to actuate the same, an actuating shaft, electrically operated mechanism 105 for causing said actuating shaft to rock and mechanism connected with said rocking shaft and with said actuating shaft and driven by said actuating shaft, for the double purpose of driving said rocking shaft and locking the same in predetermined 110 exact positions.

CHARLES J. HENSCHEL.
